DESIGN FOR A CLOCKCASE

John P. Rainbault, Bridgeport, Conn., assignor to General Electric Company, a corporation of
New York

Application July 6, 1940, Serial No. 93,479

Term of patent 7 years

To all whom it may concern:

Be it known that I, John P. Rainbault, a citizen of the United States, residing at 190 Judson Street, Bridgeport, in the county of Fairfield,
State of Connecticut, have invented a new, original, and ornamental Design for a Clockcase, of which the following is a specification, reference being had to the accompanying drawing, forming a part thereof.

The figure is a front perspective view of a clockcase showing my new design.

I claim:

The ornamental design for a clockcase, as

JOHN P. RAINBAULT.
